UNITED STATES PATENT OFFICE.

ROBERT FISCHER, OF BROOKLYN, NEW YORK, ASSIGNOR TO MAXIMILIAN H. FISCHER,
OF NEW YORK, N. Y.

CLUTCH FOR SCARF-PINS.

1,192,612.

Specification of Letters Patent. Patented July 25, 1916.

Application filed August 28, 1913. Serial No. 737,048.

To all whom it may concern:

Be it known that I, ROBERT FISCHER, a citizen of the United States, and a resident of Brooklyn, in the county of Kings and State of New York, have invented certain new and useful Improvements in Clutches for Scarf-Pins, of which the following is a specification.

This invention relates to improvements in 10 clutches for scarf pins of the type illustrated in Letters Patent of the United States Numbered 963,537, issued to me on the 5th day of July, 1910, in which a cylindrical thimble is provided with a projection for tilting a 15 perforated clutch plate carried by a frame sliding within the thimble, the said projection on the thimble being formed by indenting the thimble from the outside.

By my present invention I provide means 20 for tilting the device without striking up the projection from the thimble or indenting it from the outside thus disfiguring the exterior appearance of the clutch, and such tilting means will also serve to retain the 25 frame carrying the clutch plate in proper position to be tilted. I also provide means for engaging the clutch plate from below to move the same back to horizontal or releasing position when the frame carrying such 30 plate is pulled downwardly by the fingers of the user.

In the accompanying drawings, in which similar reference characters designate corresponding parts throughout the several 35 views: Figure 1 is a longitudinal section illustrated in the preferred embodiment of my invention, the clutch being shown in its normal tilted position; Fig. 2 is a similar longitudinal section showing the same gripping a pin; Fig. 3 is a longitudinal section 40 at right angles to Fig. 2; and Fig. 4 is a section on the line 4—4 of Fig. 3.

Referring now to these drawings, 1 designates a cylindrical outer thimble 45 preferably stamped of sheet metal and having an insertion opening 2 for the passage of a scarf pin 3.

4 indicates a tilting piece U-shaped in cross-section and having its lower end inclined upwardly as at 4^a. This tilting piece is driven into the upper end of the cylindrical thimble and is stationary with relation thereto.

5 indicates a frame which is bifurcated at 55 its upper end to provide vertical arms 5^a 5^b

which extend vertically and slide between the tilting piece and the inner surface of the thimble. Pivotaly mounted in the said frame 5 near the lower end of the bifurcated portion is a clutch plate 6 which is normally pressed into engagement with the inclined lower end 4^a of the tilting piece 4 by means of a coil spring 7 abutting between the bifurcated portion of the frame and a combined washer and straightener 8 secured at the lower end of the thimble and closing the same. The frame 5 is provided with a downwardly extending actuating stem 5^b which extends through a central opening 8^a in the combined washer and straightening piece 8 and the downwardly extending actuating stem 5^b is provided at its lower end with a ball 5^c adapted to permit pressure to be applied between the end of the operating stem and the thimble to pull the frame 75 downwardly so as to move the clutch plate out of engagement with the tilting piece and into horizontal position to release the pin. When the frame is pulled down far enough the tilting piece will engage the upper end 80 of the straightening piece 8 which will cause it to assume a horizontal position and permit the easy withdrawal of the pin.

The arrangement above described eliminates the unsightly indentation of the outer 85 cylindrical thimble, retains the inner mechanism always in proper alignment for actuation and compels a more positive gripping and releasing operation of the clutch. This arrangement also permits of a greater variation 90 in the size of the pins which may be retained within the clutch because the clutch plate, besides its simple tilting, slides upwardly on the inclined surface at the lower end of the tilting piece 4 a short distance 95 and the center of the perforation in said clutching plate may be slightly out of alignment with the center of the insertion opening without affecting the actuation of the clutch under normal conditions and still 100 making it possible to have a larger gripping aperture so as to take smaller sizes of pins without affecting its positive operation for other sizes.

Having described my invention I claim: 105

1. In a pin holder the combination with a suitable thimble, of a tilting piece connected thereto at its upper end and provided with an inclined portion, said tilting means being U-shaped in cross-section, a frame movable 110

longitudinally relatively to said thimble and having a bifurcated portion extending upwardly on opposite sides of said U-shaped tilting piece, a perforated clutch plate carried by said frame and adapted to engage the inclined face of said tilting piece, a spring for normally retaining the clutch plate in engagement with said inclined surface and means for permitting the movement by the user of such clutch plate against the action of the spring.

10 2. The combination with a scarf pin holder, of a thimble adapted to receive the end of the scarf pin, a tiltable clutch plate 15 movable longitudinally relative to said

thimble and having a perforation to receive the pin, a separate tilting piece fixed within the thimble, means for forcing the clutch plate toward said fixed tilting piece and means for permitting the user to retract the 20 clutch plate from engagement with the tilting piece.

In witness whereof, I have signed my name to the foregoing specification in the presence of two subscribing witnesses.

ROBERT FISCHER.
